PALLET

Dennis M. Melnick and Mark Kubick, Baden, Pa., as
signors to Pallet Development Inc., Ambridge, Pa.

Filed Oct. 22, 1971, Ser. No. 191,971

Term of patent 14 years

Int. Cl. D12—99

U.S. Cl. D14—3

FIG. 1 is an isometric view showing the top of a pallet employing our new design;

FIG. 2 is an isometric view, partially broken away, on the same scale as FIG. 1 showing the bottom of a pallet employing our new design.

Opposite ends and opposite sides of the pallet are duplicates.

We claim:

The ornamental design for a pallet, as shown and described.
